PATENTED FEB. 19, 1907.

H. L. CLEMENTS.

BOTTLE.

APPLICATION FILED JAN. 31, 1906.

UNITED STATES PATENT OFFICE.

HAROLD LEWIS CLEMENTS, OF DAWSON CITY, YUKON TERRITORY,
CANADA.

BOTTLE.

No. 844,579.

Specification of Letters Patent.

Patented Feb. 19, 1907.

Application filed January 31, 1906. Serial No. 298,823.

To all whom it may concern:

Be it known that I, HAROLD LEWIS CLEMENTS, a citizen of the United States, residing at Dawson, in the Yukon Territory and Dominion of Canada, have invented certain new and useful Improvements in Bottles, of which the following is a specification.

My invention relates to improvements in bottles; and the main object of the invention is the provision of a device of this character which will permit of its contents being emptied with the greatest possible ease and which will permit of liquids being poured therefrom and drained without the necessity of completely reversing the bottle.

Another object of the invention is to provide a bottle of a form convenient for packing and which will allow of heavy contents, such as pickles, being extracted with facility.

With these and other objects in view my invention consists of a bottle having one of its sides formed flat, thereby affording a plane surface from the bottom of the bottle to the mouth thereof.

My invention further consists of a bottle having means for retaining an implement thereon and certain other novel features of construction and combination of parts, substantially as herein specified.

Figure 1 is a side elevation of my improved bottle. Fig. 2 is a vertical sectional view thereof. Fig. 3 is a view of a modified form of the bottle having supporting-lugs on the flat side thereof. Fig. 4 is a view of another modification having a flat side sloping inward toward the mouth. Fig. 5 is a side elevation of a modification of the bottle provided with means for carrying a fork or similar article. Fig. 6 is a front elevation of the same. Fig. 7 is a vertical sectional view of a modified form of the invention with my improved stopper applied thereto; and Fig. 8 is an elevation of my improved bottle and cup in a carrying-case, the case being shown in section.

My improved bottle is of substantially flattened shape, having the two vertical side walls 1 and 2, and the front wall 3 is also vertical. This front wall is preferably thickened at the base, as at 4, and tapers off toward the mouth of the bottle. The rear wall 5 is bulging or swelled, forming at the top a neck portion 6. The base of the bottle is formed

with an annular rim 7, which raises the bottom and serves to strengthen it and protect it against breakage. By sloping the front wall it will be readily observed that the contents of the bottle may be removed with great facility and without necessitating the complete upturning of the bottle.

As shown in Fig. 3, supporting-lugs 8 may be formed on the front side at the mouth and base of the bottle to facilitate the flow of the contents and also to support the bottle in a horizontal position and prevent overturning of the same.

In Fig. 4 I have shown a bottle having the front wall inclined inward, thereby providing a broad supporting-base.

In bottles containing pickles and similar products some implement is necessary for extracting the same from the bottle. In order to keep such an implement associated with the bottle, I have formed the same with extensions 9 at the mouth and base thereof, having seats or recesses 10 provided in said extensions. Adapted to be engaged by and carried in said extensions is the fork 11, having its ends engaged in the recesses in said extensions. The recess in the upper extension is of greater depth than the lower one, to permit ready withdrawal of the fork or other implement. As the fork need not project beyond the line of the extensions, it is protected against injury or accidental displacement.

The form of my invention shown in Fig. 7 has an annular ring 12, of rubber or similar material, secured around the neck thereof. A plate 13 covers the mouth of the bottle, 90 and a flexible cap 14, secured to the plate, embraces the neck of the bottle and overlaps the annular ring thereon.

In order to readily transport the bottle and contents, I provide a rectangular carrying-case 15, having a tight-fitting cover 16. The bulging rear wall of the bottle provides a space 17 at the top of the case, and in this space is adapted to fit the cup or similar utensil 18.

From this description, taken in connection with the drawings, it will be evident that I have provided a cheap and durable bottle which is convenient for handling and packing and which accomplishes all the objects hereinbefore stated.

I claim—

1. A bottle having one of its sides flat and tapering from the base toward the mouth thereof.	flat wall tapering from its base toward the mouth.
5 2. A bottle having a bulging wall, and a flat wall sloping toward the mouth of the bottle.	6. A bottle having an exterior vertical flat wall tapering in thickness from the base to the mouth.
10 3. A bottle having flat side walls, bulging rear wall, and flat tapering front wall.	In testimony whereof I affix my signature in presence of two witnesses:
4. A bottle having flat side walls, and a sloping front wall.	HAROLD LEWIS CLEMENTS.
5. A bottle having a bulging wall and a	Witnesses: THOMAS A. FIRTH, CARLTON WOODWARD.
